207,406

MULTIPLE UNIT BREAD BAKING PAN

Warren C. Van Meter, 4800 Oaklawn Drive,
North Little Rock, Ark. 72118

Filed July 14, 1966, Ser. No. 3,073

Term of patent 14 years

(Cl. D44—1)

Fig. 1

Fig. 2

Fig. 3

I claim:

The ornamental design for a multiple unit bread baking pan, as shown.
